UNITED STATES PATENT OFFICE.

MORRIS SEGAL, OF NEW YORK, N. Y.

CRIB.

No. 907,295.

Specification of Letters Patent

Patented Dec. 22, 1908.

Application filed July 24, 1908. Serial No. 445,273.

To all whom it may concern:

Be it known that I, MORRIS SEGAL, a citizen of Roumania, residing at New York city, in the county of New York and State of New York, have invented certain new and useful Improvements in Cribs; and I do hereby declare the following to be a full, clear, and exact description of the invention, such as will enable others skilled in the art to which it 10 appertains to make and use the same.

This invention relates to improvements in cribs, and particularly to collapsible cribs and cradles for small children.

The object of the invention is the provision of collapsible sides for a crib, and means for positively locking the sides in an expanded or open position.

Another object of the invention is the arrangement of collapsible sides, pivotally mounted levers, and a stop for locking the sides in an expanded position, and pivotally mounted supporting members for forming the bottom or support of the crib.

A further object of the invention is the provision of a crib having sides of a lazy-tong construction, jointed longitudinal top bars for locking the lazy tongs in a distended position, means for holding the longitudinal jointed bars in a fixed position, and a plurality of pivotally mounted supports connected with the lazy tongs for forming the bottom of the crib.

With these and other objects in view the invention comprises certain novel constructions, combinations, and arrangement of parts as will be hereinafter more fully described and claimed.

In the accompanying drawings: Figure 1 is a side elevation of a crib embodying the features of the present invention. Fig. 2 is a side view of the crib in a collapsed position. Fig. 3 is a fragmentary sectional view approximately on line 3—3 of Fig. 1. Fig. 4 is a detail perspective view of a rest for receiving a pair of pivotally jointed locking bars. Fig. 5 is a detail fragmentary side elevation of one corner of one of the end members of the crib disclosing certain features of the invention.

Referring to the drawing by numerals, 1 and 2 indicate the end pieces or members of the crib or cradle that may be constructed of any desired material, but preferably of metal. The end pieces are formed from 55 angle bars 3 that are bent to form a square or rectangular construction as may be de-

sired, and then have secured thereto a plate 4 as clearly seen in Fig. 5. The angle iron 3 is cut at 5 so as to be easily bent for forming substantially a rectangular construction, and yet present an even outer surface. The plate 4, together with the angle iron 3, when secured together, form a rigid but comparatively light end piece, and one that will not easily become damaged. Secured to the end 65 piece 1 is a rocker 6 that is preferably formed from a bar of metal and rigidly secured to angle iron 3 of end 1 by rivets or other desired securing means. End 2 has secured thereto a rocker 7 similar to rocker 6 so as to 70 act in conjunction therewith when the device is being used as a cradle. When the device is used simply as a crib or bed for children the rockers 6 and 7 may be omitted, and simply ordinary legs or supports used in 75 place thereof.

Connecting ends 1 and 2 are a pair of lazy tongs 8—8. Pivotally mounted extensions 9—9 and 10—10 are pivotally connected with some of the end bars of the lazy tongs, 80 and the remaining end bars of the lazy tongs are connected by bars 11—11 and 12—12 with sliding guides 13—13 and 14—14 secured to ends 1 and 2 respectively. Bars or pins 11—11 and 12—12 not only connect 85 some of the end members of the lazy tongs with guides 13—13 and 14—14, but also pass through pivotally mounted locking bars 15—15 and 16—16. Locking bars 15—15 and 16—16 are pivotally connected or jointed 90 at 17—17 and are arranged to rest in sockets or hooks 18—18 secured to the respective lazy tongs 8—8. The sockets or hooks 18—18 are arranged so that the locking bars 15—15 and 16—16, when their ends are positioned 95 therein, will be past a dead center, and will consequently lock the lazy tongs in an expanded position.

Pivotally mounted to the lazy tongs at the lower joining of the respective bars making 100 up the tongs are a plurality of supports 19. The supports 19 preferably extend downward from their pivotal joint a short distance, and then at right angles across the crib from one lazy tong to the other and 105 form the supports for the mattress or other bedding used in the crib. In order to form additional support for any matter placed in the crib a plurality of flexible straps 20 are secured to the respective ends 1 and 2 and 110 extend for the full length of the crib as clearly seen in Fig. 1.

By this construction and arrangement a crib or cradle is presented in which means are arranged for positively holding the crib in an expanded position and yet be always in a condition for ready collapsing. When it is desired to collapse the crib the bars 15-15 and 16-16 may be pulled out of the sockets 18-18 and forced past the same in a downward direction, the pivotal mounting at pins 11-11 and 12-12 being sufficiently loose, when taken with the springs of the bars, to permit such movement. The ends 1-1 then may be forced together and the crib collapsed to the position shown in Fig. 2, the locking bars 15-15 and 16-16 pointing in a downward direction. If desired the locking bars 15-15 and 16-16 may be raised above their respective sockets 18-18 and then the crib collapsed and the bars 15-15 and 16-16 pointing in an upward direction.

By this construction and arrangement jointed longitudinal bars are presented which rest in sockets and form locking means for holding the crib in an expanded condition and pivotally mounted supports that remain in a horizontal plane at all times regardless

of whether or not the crib is expanded or collapsed.

What I claim is:

1. In a device of the character described, end members, lazy tongs connecting said end members, and means for locking said lazy tongs in an expanded position comprising a pair of folding bars and a retaining hook for said bars.

2. In a crib, a pair of end members, lazy tongs connecting said end members, longitudinally disposed pivotally mounted bars connected to said lazy tongs near the upper edge thereof, a hook for receiving and holding the jointed ends of said bars for causing said bars to lock said lazy tongs in an expanded position, and means secured to said lazy tongs for forming a support for articles placed in said crib.

In testimony whereof I affix my signature in presence of two witnesses:

MORRIS SEGAL.
